OSCILLATOR CIRCUIT

James L. Potter, Iowa City, Iowa

Application April 17, 1937, Serial No. 137,463

7 Claims. (Cl. 250—36)

This invention relates to a circuit arrangement adaptable for incorporation in oscillators of the type used to provide a timing axis for cathode ray tubes and the like, or in multivibrator and similar systems.

It is an object of my invention to provide a relatively simple and inexpensive arrangement or combination of parts in a circuit which will perform a sequence of operations in such a periodic manner as to constitute it an oscillator or the like, and which will eliminate the difficulty present in other such systems arising from the interaction between the local oscillator and the external circuit used to stabilize or control it, as for example, by regulating the frequency.

It is a further object of my invention to provide an element of an oscillator circuit which shall have generated across it a highly peaked wave of voltage suitable for biasing a cathode ray tube as used in television to cut-off during the return sweep, thus eliminating the blur or trace.

It is a further object of my invention to provide a simple, inexpensive and reliable means for providing both a linear sweep voltage and, separately, a highly peaked voltage which may be employed for cut-off to eliminate the return trace as above set forth.

With these and other objects in view, my invention consists in the arrangement and combination of the various parts of my oscillator circuit, whereby the objects contemplated are attained, as hereinafter more fully set forth, pointed out in my claims, and illustrated in the accompanying drawing, in which:

Figure 1 is a diagrammatic representation of a circuit embodying my invention.

Figure 2 is a curve showing the variation in voltage with time across the terminals of the main control condenser or condensers used in my circuit.

Figure 3 is a curve showing the variation in voltage with time between the grid terminal of one of the vacuum tubes employed in my circuit and ground.

Figure 4 is a curve showing the variation in voltage with time appearing across the common cathode dropping resistor in my circuit.

Figure 5 is a curve showing the variation in voltage with time between the plate of one vacuum tube and ground.

The diagram shown in Figure 1 embodies my invention in a circuit suitable for providing the time axis for deflecting the electron beam in a cathode ray tube, such as is used for ordinary

oscillographic purposes and television where it is desired to have the deflection of the beam essentially linear with respect to time. Under most circumstances this requires the application of a potential difference which is also linear with respect to time. In the circuit shown in Figure 1, this result is accomplished by charging the condenser 10 through a variable resistance 12 from a source of unidirectional current 14, which may be a battery, rectifier or other suitable source.

The voltage rise across the condenser 10 is essentially linear with respect to time since the condenser charges only to about fifteen per cent or less of its final value. During the charging period of the condenser 10, the vacuum tube 16 draws no plate current since it is blocked by the nature of the circuit controlling grid of said tube. While the condenser 10 is charging through the variable resistance 12, the condenser 18, which has previously been charged, is gradually discharging through the resistor 20 and continues to discharge until the tube 16 starts to draw plate current.

This point occurs when the potential of the condenser 10 and hence the plate to ground voltage of the tube 16, has reached such a value that the voltage drop across the resistor 20 is no longer sufficient to bias the tube 16 to cut-off.

The plate current, or discharge current of the condenser 10, which then begins to flow, passes through the resistance 22 and develops thereon a potential of such polarity as to cause a vacuum tube 24 to draw less current, that is, the negative bias on the tube 24 is increased and the plate current consequently is decreased.

Inasmuch as the plate current through the tube 24 flows through the resistance 26, a reduction in the current reduces the voltage drop across the resistance 26 and causes the plate end of the resistor 26 to become more positive with respect to ground (see Figure 5). The increased potential between these two points results in the charging of the condenser 18 by current flowing through the resistor 26 and also through the resistor 20. Inasmuch as the grid of the tube 16 is positive with respect to the cathode during this part of the cycle (see Figure 3) grid current flows and comprises a part of the charge. When the grid of the tube 16 becomes more positive, the conductivity of the tube increases and it will be seen that the effect is cumulative. When the plate current or discharge current through the tube 16 starts to decrease, due to the decreasing potential difference across the condenser 10, as it discharges, the voltage drop across the resistance 26

22 decreases and the grid potential of the tube 24 shifts positively with respect to the cathode or the cathode becomes more negative with respect to the grid, causing the tube 24 to draw more plate current and the drop across the resistance 26 to increase.

The potential between the plate of the tube 24 and ground is thereby necessarily decreased and because of this decreased potential the 10 charge on the condenser 18 decreases. The charge flowing out of the condenser 18 results in a flow of current through the resistance 20 in such a direction that the grid of the tube 16 becomes increasingly negative with respect to the 15 cathode, thereby ultimately blocking the tube 16.

Under these conditions the condenser 10 starts charging again and the process is repeated.

It will be seen that this cycle of operations results in a charging of the condenser 10 by current flowing through the resistance 12 from the source 14. Before the charge progresses to a point at which the charging current would cease to be substantially uniform, the associated circuit operates to render the tube 16 conducting 25 and consequently to act as a shunt or short circuit resulting in the very rapid discharge of the condenser 10. The cycle is repeated and results in a variation of potential across the terminals of the condenser 10, which is represented by the 30 graph in Figure 2. This is the conventional saw tooth wave of voltage, such as is used to provide a time axis for cathode ray tubes with deflection plates.

Inasmuch as the variation from maximum to 35 minimum of the voltage appearing across the condenser 10 may not be sufficient for deflection of a cathode ray beam, without some form of amplification, an amplifier may be provided to increase the magnitude of the sweep voltage. The circuit shown in Figure 1 has been divided 40 into two principal parts by dotted lines, that enclosed by the rectangle A being the sweep circuit proper and the portion enclosed in the rectangle B constituting a one stage amplifier suitable for 45 providing the amplification which may be necessary. Any number of stages can be provided in this way.

It will be noted that the circuit is adapted to the use of the so-called "hard" tubes or high 50 vacuum tubes, as opposed to the "soft" or gaseous type of tubes. It has been found that the hard tubes give more satisfactory and consistent operation.

A valuable feature of this circuit as I have 55 shown it is that the voltage occurring across the resistance 22 has the peculiar wave form indicated in Figure 4, having peaks of substantial magnitude but of short duration, in time, relative to the time between peaks. A periodic peaked wave of this kind may be very useful in certain 60 applications in which a sweep circuit is employed, as for example in television or other cathode ray tube applications. It is frequently desirable to apply a peaked voltage to the intensity 65 control of the cathode ray tube in such a manner as to extinguish or cut off the beam during the return trace. The circuit as I have shown it supplies the linear voltage necessary for transverse sweep purposes, across the condenser 10 or the output terminals 28 and 30, and also across the resistor 22, exhibits a peaked 70 voltage such as is shown in Figure 4, which may be applied through suitable amplification devices to the intensity control electrode of the cathode ray tube.

My circuit possesses peculiar advantages as regards synchronizing or interlocking its frequency with that of some external source of periodically recurring or alternating voltage. Such a voltage may be introduced into the circuit shown by connection to the terminals 32 and 34. 5 It will be observed that the voltage thus applied appears on the grid of the tube 24.

An advantage of my circuit arrangement over circuits of this type which have heretofore been used, lies in the fact that circuits previously used have applied both the synchronizing and feed-back voltage to the grid of the tube and in most cases both of these voltages have been made effective in the grid circuit by passing through the 10 same resistor or impedance. Consequently variations in the electrical characteristics of the external circuit affect the local oscillator and sometimes cause unsatisfactory operation.

In my circuit the synchronizing potential appears 20 between the grid of the tube 24 and ground, the ground potential being represented by the conductor 36. The feed-back potential, that is, the voltage necessary to cause phase inversion and oscillator operation, appears between cathode and ground, that is across the resistor 22. In my circuit there is no interaction between the grid-ground connection and the cathode-ground connection so that operation of the local oscillator is entirely independent of random or other 30 undesirable changes in the electrical characteristics of the circuit from which the synchronizing voltage is obtained.

The resistance 12 may be replaced by a vacuum tube such as a constant current pentode to give 35 a constant current charging of condenser 10 and hence a more nearly linear sweep. The two tubes 16 and 24 may be enclosed in the same envelope to reduce the number of tubes and conserve space. This may be accomplished by using duplex triodes in the form of such standard makes as tubes No. 53 and No. 6A6. The tubes 16 and 24 may be either indirectly heated triodes as shown, tetrodes, pentodes, or any tube that functions as above mentioned. Various combinations 45 of the above tubes have been successfully employed. By placing a resistance or other impedance of desired characteristic in series with or in place of the condenser 10, special wave forms may be obtained such as may be required 50 in connection with electromagnetic deflection, to which the above circuit may be adapted.

Although I have shown my invention in Figure 1 in a form applicable as a sweep circuit, for use with cathode ray tubes, it is by no means limited 55 to such an application but may be used as a special wave shaping circuit for television, employing the peaked impulses generated across the resistance 22. The same type of circuit with or without the amplifier may be connected in cascade 60 for obtaining multiple impulses or sub-multiple impulses as a multivibrator circuit, to generate synchronizing voltages for both vertical and horizontal deflection in television.

By removing the condenser 10 and making the 65 resistance 12 a suitable value, the arrangement can be used as a straight multivibrator circuit and when used as such will eliminate the necessity of a buffer tube, inasmuch as there is no interaction between the synchronizing signal and the feed-back, such as occurs with the condenser feed-back as used in the standard multivibrator circuit.

Some changes may be made in the construction and arrangement of the parts of my device with- 75

out departing from the real spirit and purpose of my invention and it is my intention to cover by my claims any modified forms of structure or use of mechanical or electrical equivalents which 5 may be reasonably included within their scope.

I claim as my invention:

1. In a sweep circuit, a condenser, a resistance and a source of unidirectional current connected in series, an electron tube, plate, grid and cathode 10 elements in said tube, said plate and cathode elements being connected in series with said condenser, a resistance connected between said grid and cathode elements, a second electron tube, a plate and cathode in said tube, a capacitive coupling of said grid to said plate of said second electron tube, a resistance between said plate of said second electron tube and one terminal of said source of unidirectional current and a common resistance in the connection of the cathodes 15 of both said electron tubes to the other terminal of said source of unidirectional current.

2. In an electron tube circuit, a source of unidirectional current, a condenser and an impedance, said condenser and said impedance being connected in series with said source, an electron tube, cathode, grid and plate elements therein, a second impedance, said plate and cathode elements and said second impedance being connected in series with said condenser, a third impedance 20 between the grid and cathode elements of said electron tube, a second electron tube, cathode and plate elements therein, a fourth impedance coupling said grid of said first mentioned tube to said plate of said second electron tube, and a fifth impedance connected between the plate of said second electron tube and said source of unidirectional current, said cathode of said second electron tube being connected to one terminal of said second impedance, and said source of unidirectional current being connected to the other terminal of said second impedance.

3. The combination of a condenser, means for charging said condenser from a source of current at a substantially constant rate, a vacuum tube having at least three elements therein, its plate-cathode circuit being connected across said condenser, an oscillator circuit connected to the grid of said tube for maintaining said grid highly negative during the charging interval of said 45 condenser and means in the oscillator circuit for rapidly driving said grid positive to discharge the condenser at predetermined intervals, said oscillator circuit comprising a second vacuum tube, the plate of said second vacuum tube being connected to the grid of said first mentioned vacuum tube through a condenser, and an impedance, the cathodes of said second vacuum tube and said first mentioned vacuum tube being both connected through said impedance to a source of suitable current.

4. A combination of a condenser, a source of current, means for charging said condenser from said source, a vacuum tube having at least three elements therein, its plate-cathode circuit being connected across said condenser and an oscillator circuit connected to the grid of said tube for con-

trolling the potential of said grid relative to the cathode of said tube, said oscillator circuit comprising a second vacuum tube, the plate of said second vacuum tube being coupled to the grid of said first mentioned vacuum tube, and the cathodes of said tubes being connected together, a resistance between said cathodes and one terminal of said source, and a potentiometer having one end terminal connected with said one terminal of said source and having an intermediate terminal connected with the grid of said second tube. 5

5. In a sweep circuit, a condenser, a resistance and a source of unidirectional current connected in series, an electron tube, plate, grid and cathode elements in said tube, said plate and cathode elements being connected in series with said condenser, a resistance connected between said grid and cathode elements, a second electron tube, plate, grid and cathode elements in said second tube, a capacitive coupling of said grid of said first tube to said plate of said second electron tube, a resistance between said plate of said second electron tube and one terminal of said source of unidirectional current, a connection between the cathodes of said tubes, a resistance between 25 said connection and the other terminal of said source and a potentiometer having one terminal connected with said other terminal of said source and another terminal connected to said grid of said second electron tube. 20

6. In a multivibrator circuit, an electron tube, plate, grid and cathode elements therein, a source of unidirectional current, a resistance between the plate of said tube and one terminal of said source of unidirectional current, a resistance between 30 cathode and grid terminals of said tube, a second electron tube, plate and cathode elements therein, a condenser coupling the grid of said first tube to the plate of said second tube, a resistance between the plate of said second tube 35 and said one terminal of said source of unidirectional current, a resistance having one end connected to the cathodes of both said tubes and its other end connected to the other terminal of said source of unidirectional current, and a second condenser having one terminal thereof connected to the plate of said first tube and its other terminal connected to said other terminal of said source of unidirectional current. 40

7. In an oscillator circuit, a condenser, a current limiting device and a source of unidirectional current in series, an electron tube, cathode, grid and plate elements therein, an impedance, said plate and cathode elements and said impedance being connected in series with said condenser, a second impedance between the grid and cathode elements of said electron tube, a second electron tube, cathode and plate elements therein, a condenser coupling said grid of said first mentioned tube to said plate of said second electron 50 tube, a third impedance connected between the plate of said second electron tube and said source of unidirectional current, and a connection between the cathode of said first mentioned tube and the cathode of said second tube. 55
